UNITED STATES PATENT OFFICE.

HORATIO S. EARLE, OF DETROIT, MICHIGAN.

DESIGN FOR A GRASS-CUTTING BLADE.

SPECIFICATION forming part of Design No. 30,478, dated April 4, 1899.

Application filed March 6, 1899. Serial No. 708,040. Term of patent 14 years.

To all whom it may concern:

Be it known that I, HORATIO S. EARLE, a citizen of the United States, residing at Detroit, in the county of Wayne, State of Michigan, have invented and produced a new and original Design for Grass-Cutting Blades; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to a new and original design for grass-cutting blades.

In the accompanying drawings, Figure 1 is an elevation of one side of my design. Fig. 2 is an elevation of the reverse side thereof. 20 Fig. 3 is an enlarged transverse section, as on line 3 3 of Fig. 2. Fig. 4 is an enlarged transverse section, as on line 4 4 of Fig. 2.

The leading feature of my design consists of a curved blade provided with a depression 25 forming in one face of said blade a longitudi-

nal channel which extends into the shank and producing upon the obverse face of said blade a raised bead. The faces of said blade are flat on either side of said channel and bead, while the back of the blade is provided with 30 a raised flange.

A designates the main portion of the blade; B, the shank thereof; a, the channel formed in one face of said blade and shank; b, the bead formed upon the opposite face of said 35 bead and shank, and C the raised flange at the back of said blade, the whole presenting to the eye a harmonious and ornate figure, as shown in the drawings.

Having described my design, what I claim 40 is—

The design for a grass-cutting blade, substantially as herein shown and described.

In testimony whereof I sign this specification in the presence of two witnesses.

HORATIO S. EARLE.

Witnesses:

E. S. WHEELER,
M. A. MARTIN.
